(57) **CLAIM**

The ornamental design for a portable office/meeting room, as shown and described.

DESCRIPTION

FIG. 1 is a perspective view of a portable office/meeting room, showing our new design;

FIG. 2 is another perspective view thereof, from a different angle than FIG. 1;

FIG. 3 is a front view thereof;

FIG. 4 is a back view thereof;

FIG. 5 is a right side view thereof;

FIG. 6 is a bottom view thereof;

FIG. 7 is an enlarged top view of the corner of inset 7 of FIG. 1;

FIG. 8 is a top view thereof;

FIG. 9 is a left side view thereof;

FIG. 10 is an enlarged view of a bottom corner of inset 10 of FIG. 1;

FIG. 11 is a perspective view of a second embodiment of the portable office/meeting room of FIG. 1, showing our new design;

FIG. 12 is another perspective view thereof, from a different angle than FIG. 11;

FIG. 13 is a front view thereof;

FIG. 14 is a back view thereof;

FIG. 15 is a right side view thereof;

FIG. 16 is a bottom view thereof;

FIG. 17 is an enlarged top view of the corner of inset 17 of FIG. 11;

FIG. 18 is a top view thereof;

FIG. 19 is a left side view thereof; and,

FIG. 20 is an enlarged view of a bottom corner of inset 20 of FIG. 11.

1 Claim, 20 Drawing Sheets
